UNITED STATES PATENT OFFICE.

JAY G. ROBINSON, OF CHICAGO, ILLINOIS.

FIRE DOOR.

1,407,222.

Specification of Letters Patent. Patented Feb. 21, 1922.

Application filed August 18, 1919; Serial No. 318,254. Renewed December 12, 1921. Serial No. 521,927.

To all whom it may concern:

Be it known that I, JAY G. ROBINSON, a citizen of the United States, residing at Chicago, in the county of Cook and State of Illinois, have invented certain new and useful Improvements in Fire Doors; and I do hereby declare the following to be a full, clear, and exact description of the invention, such as will enable others skilled in the art 10 to which it appertains to make and use the same.

The invention relates to mechanically operated doors and more particularly to doors for furnaces, locomotives, boilers and 15 the like.

The particular object of my invention, broadly stated, is to provide means for maintaining a furnace door in a partially opened position and specifically to provide means in 20 connection with fluid operated doors to "crack" or maintain the same in a predetermined partially opened position, said means acting to prevent the door operating fluid pressure from returning the mechanism 25 to normal or closed position. To this end I provide the said fluid pressure mechanism with means to engage a movable element thereof, said means acting against the fluid pressure and preventing the closing of the 30 door beyond a certain amount, said means being movable to and from operative position at will.

The nature of the invention will be apparent from the more detailed description of 35 the same when considered in connection with the accompanying drawing wherein a single embodiment of the invention is illustrated, and in which;

Figure 1 is a fragmentary view of a well 40 known fluid operated door mechanism showing the invention applied thereto, and

Figures 2 and 3 are respectively, views in 45 front and side elevation of a portion of the device illustrated in Figure 1 showing the invention on a slightly larger scale.

Throughout the specification and drawings like parts are designated by like reference characters.

In the drawings, 1 designates the door 50 ring or frame which is adapted to be fastened to a furnace or locomotive fire box. Door guides 2, 2 (only one of which is shown) are preferably connected, in any suitable manner to the sides of the said ring. 55 These guides may be arranged vertically, as shown, so that the furnace door or doors

will move parallel with the said guides. The doors 3, 3 may be and preferably are, slidably mounted in the said guides 2, 2, and each is provided with a pivot member 4 and 60 5 respectively, to which may be connected, as for example by the links 6 and 7 respectively, the levers 8 and 9 of the door opening or operating mechanism. The lever 8 is preferably connected adjacent its outer end to 65 a bent connecting lever 10, said lever 10 being pivotally connected at its opposite end to the lever 9.

To one of the door guides 2 is connected 70 the cylinder 11 of the door opening and closing mechanism, said cylinder, except as hereinafter noted being constructed and arranged substantially as shown and described in the patent to Shoemaker Number 922,530, dated May 25, 1909.

Passing through a suitable opening in the lower end of the cylinder 11 and normally positioned adjacent to the said end of the cylinder is the bifurcated or clevis end 12 of the piston rod 13. The said clevis is 80 adapted to receive one end of a link 14 which is connected to the clevis by means of the clevis pin 15. The lower end of the said link 14 is pivotally connected to the lever 10 intermediate the ends of the latter so that a 85 downward movement of the piston rod 13 will cause the said lever to operate the levers 8 and 9 and force the doors to open position. An upward movement of the piston rod 13, from the position just described, will cause 90 the lever 10 to again operate the other levers but in the opposite direction so that the doors are forced to closed position.

To the lower end of the cylinder 11, in place of the usual end closure, I provide a 95 bracket 16 which may constitute a cylinder head connected to the cylinder by means of the bolts 17 or other equivalent fastening means. The said bracket preferably has a flat upper face which closes the lower end of the cylinder and is also provided with a downwardly extending lip or flange 18 which is preferably provided on its inner face with a pair of intersecting grooves or recesses 19 and 20. The recess 19 extends at an angle 105 to the vertical axis of the cylinder 11 while the recess 20 extends parallel with the piston rod 13 and is adapted to overlie the path of travel of the pin 15. Passing through the flange 18 and leading to a point at the intersection of the said grooves is an opening 21 110 which is circular in cross-section. The

cracking pawl 22, i. e., the lever by which the doors are adapted to be maintained in cracked or slightly open relation, is preferably formed as an L-shaped piece, having a 5 cylindrical shank 23 and a rectangular foot 24. The said pawl is adapted to be adjustably locked within either groove by means of the spring 25 which surrounds the outwardly projecting end of the shank 23 and 10 which is maintained in position under compression by the washer and key 26. The rectangular foot 24 of the said pawl is adapted to closely fit between the side walls of the grooves 19 and 20 so as to be held 15 from turning therein when in either position.

The groove 20 is in alinement with the clevis pin 15 and the end of the foot 24 when in vertical position is adapted to engage the said pin and hold the same from upward 20 movement. The length of the foot 24 is preferably so adjusted as to engage the clevis pin and arrest the movement of the piston rod 13 when the doors are cracked or separated a distance of four inches. It 25 is to be understood, however, that this distance may be varied by lengthening or shortening the said foot 24 so as to hold the doors in any desired position. If desired the end of the said foot may be curved as shown at 30 27 so as to conform to the curvature of the clevis pin 15.

Normally the cracking pawl lies within the groove 19 and when it is desired to "crack" the furnace doors, the doors are 35 forced to open position and the stem 23 of the pawl 22 is pushed inwardly to release the foot 24 from the groove 19. The pawl is then rotated to a position in alinement with the groove 20 and then released, the 40 spring 25 thereupon forcing the foot 24 into the said groove. The door mechanism is then released and on the upward movement of the piston rod 13 the cracking pawl 22 engages the pin 15 and arrests the doors in 45 spaced relation. To return the pawl 22 to normal position the doors are again opened and the operation reversed.

Having now described my invention, what I claim and desire to secure by Letters Patent is:

1. The combination with a fire door and fluid controlled means for opening and closing the same, of means for maintaining said door in a predetermined open position, said 50 last named means being mounted on said first named means and adapted to be interposed between parts thereof.

2. The combination with a fire door and fluid controlled means including a cylinder 60 for opening and closing said door, of means for holding said door in a predetermined

open position, said last named means being carried by said cylinder and adapted to engage a movable element of said fluid controlled means.

3. The combination with a fire door and fluid operated means for opening and closing said door said means involving a cylinder and a plurality of levers, of means movably connected to said cylinder for preventing said fluid operated means from completely closing said door.

4. The combination with a fire door comprising a plurality of sliding members and fluid controlled mechanism for operating 75 said sliding members, and means movable to operative and inoperative positions and adapted when in operative position to engage an element of said mechanism to prevent the closing of said members beyond 80 a predetermined amount.

5. The combination with a fire door comprising a pair of sliding door members and fluid operating mechanism for opening and closing the same, said mechanism including 85 a cylinder and means comprising a rotatable spring pressed lever carried by said cylinder and adapted to be rotated to engage a portion of said mechanism to prevent the closing of said door members.

6. The combination with a fire door and fluid controlled means for opening and closing the same, of spring pressed means movable to and from operative position, said means being adapted to engage a portion of 95 said fluid controlled mechanism to prevent the closing of said door, and means formed on said fluid pressure means for locking said spring pressed means in operative position.

7. The combination with a fire door comprising a pair of sliding door members, and fluid operated mechanism for opening and closing the same, said mechanism including a cylinder, a rotatable L-shaped lever carried by said cylinder and adapted in one position to engage a portion of said mechanism to prevent the closing of said door members.

8. The combination with a fire door comprising a pair of sliding door members, fluid operated mechanism for opening and closing 110 the same, said mechanism including a cylinder, a bracket carried by said cylinder, said bracket being provided with angularly disposed recesses, a rotatable L-shaped lever carried by said bracket, a portion of the 115 said lever being adapted to fit within either of the said recesses, the lever being adapted in one position to engage a portion of said mechanism for preventing closing of the said door members.

In testimony whereof I affix my signature.
JAY G. ROBINSON.
